ARTICLE DISPENSER OR SIMILAR ARTICLE

Kenneth D. Olsen, Madison, N. J.

Application January 31, 1955, Serial No. 34,304

Term of patent 14 years

(Cl. D58—12)

Fig. 1.

Fig. 3.

Fig. 2.

Figure 1 is a front elevational view of an article dispenser or similar article, showing my new design;

I claim:

The ornamental design for an article dispenser or similar article, as shown.
